UNITED STATES PATENT OFFICE

2,274,737

PHOTOELECTRIC TRANSMITTER

Louis M. Potts, Evanston, Ill., assignor to Teletype Corporation, Chicago, Ill., a corporation of Delaware

Application December 20, 1937, Serial No. 180,716

38 Claims. (Cl. 178—17)

This invention relates to printing telegraph machines and particularly to transmitting apparatus for impressing telegraph signals upon a communication channel.

More specifically, the invention pertains to the scanning of message indicia by photo-electronic means and the initiation of telegraph impulse conditions in accordance with the message indicia scanned.

An object of the invention is to scan message indicia arranged on page form paper in lines according to the arrangement of, and if desired, in conjunction with the printed message which the indicia represent.

Another object of the invention is to control the progress of the message page through the scanning transmitter by electrical impulse conditions generated thereby.

Another object of the invention is to supplement the impulse conditions originated by the page scanner by impulse conditions introduced by an auxiliary photo-electronic mechanism.

Another object of the invention is to receive and store a plurality of message pages for delivery successively to the page scanner mechanism and to deliver the pages thereto in succession automatically.

The invention features a photo-electric scanning system in which the scanning of message index elements successively is accomplished by shutters comprising apertured endless flexible bands similar in structure to photographic focal-plane shutters arranged to travel at right angle to the direction of travel of the message page.

The invention also features a selector mechanism local to the transmitter to which all of the signals generated therein are applied and which is effective in response to certain of said signals to control the handling of the message page and the admission of stored pages into the transmitter.

A related invention, which contemplates the transmission of impulses corresponding to signals carried by a tape and scanned by photo-electronic means, is disclosed in copending application Serial No. 48,098, filed November 4, 1935, by Louis M. Potts.

Briefly, in accordance with the preferred embodiment of the present invention, there is provided a pair of endless bands spaced apart a distance depending upon the width of a page upon which signals to be transmitted have been impressed, and supported for movement in parallel paths by two pairs of sprockets or pulleys

carried by two shafts. The belts or bands are provided with feed pins for receiving and holding in proper alignment a message page. A pair of endless scanning belts extend transversely of the page supporting belts. One of the scanning belts is provided with an aperture arranged to register with all of the signal-impulse elements of a code-signal combination simultaneously, and the belt is moved step by step to bring the aperture into registry with the code-signal combinations successively. The other belt is provided with a plurality of apertures in stepped or staggered arrangement so that the signal-impulse elements of a code-signal combination may be scanned successively by the several apertures of the set. This belt receives continuous movement when operating. A photo-electric system comprising a source of light and a photo-electric cell is arranged in proximity to the scanning belts so that impulses may be generated in accordance with the signal-impulse elements scanned. The impulses thus generated may be amplified and impressed upon a communication channel.

The code-signal combinations generated, in addition to being impressed upon a communication channel, are impressed upon the windings of the selector magnet of a selector mechanism local to the transmitter. The selector mechanism may be similar to that employed in printing telegraph receiving units and is provided for controlling certain functions that require performance in the transmitter mechanism. The advancement of the page step by step through the transmitter to effect the transmission of the lines of signal combinations and the feeding out of the page from the transmitter after the complete message has been transmitted, are controlled by the selector mechanism.

A message storage magazine is mounted adjacent to the transmitter and is provided with sprocket feed mechanism for engaging a plurality of message pages arranged overlapping for advancement simultaneously and delivery successively to the page handling bands of the transmitter. The feed mechanism of the page storage magazine is actuated by the page-handling band mechanism of the transmitter. The message storage and message transmitting mechanism is automatically arrested when the last page of message material has been transmitted and is automatically restarted by the placing of a page in the storage magazine.

For a full and complete understanding of the invention, reference may be had to the follow-

ing detailed description to be considered in conjunction with the accompanying drawings wherein,

Fig. 1 is a fragmentary plan view having various portions broken away to reveal structural details;

Fig. 2 is a fragmentary front elevational view having detailed portions at the right side thereof broken away and in section;

Fig. 3 is a fragmentary side elevational view with the assembly of shafts 31 and 92 in quarter section as best indicated by line 3—3 of Fig. 2;

Fig. 4 is a sectional view taken approximately on line 4—4 of Fig. 3;

Fig. 5 is a sectional view taken approximately on the line 5—5 of Fig. 2;

Fig. 6 is a sectional view taken approximately on the line 6—6 of Fig. 3;

Fig. 7 is a fragmentary rear elevational view showing the selector mechanism in an opposite direction from that of Fig. 2;

Fig. 8 is a fragmentary plan view of a message storage magazine having portions broken away to reveal structural details;

Fig. 9 is an elevational view of the message storage magazine shown in Fig. 8 with certain parts broken away or in section to show structural details;

Fig. 10 is a detail view of the magazine operating mechanism appearing at the right of Fig. 9, showing the mechanism at a different time in a cycle of operation;

Fig. 11 is an elevational view taken approximately on the line 11—11 of Fig. 2;

Fig. 12 is a schematic wiring diagram of the electrical communication and control system;

Fig. 13 is a detail view of message storage magazine pawl and ratchet feed mechanism shown in Figs. 8 and 9;

Fig. 14 is a detailed plan view of a fragment of one of the scanning bands;

Fig. 15 is a sectional view taken approximately on the line 15—15 of Fig. 1, showing two different operative conditions; and,

Fig. 16 is a sectional view taken approximately on the line 16—16 of Fig. 3.

Referring now to the drawings in which like reference numerals designate corresponding parts throughout the several views and particularly to Figs. 1 and 2, the reference numeral 21 designates an electric motor, the rotor shaft 22 of which carries a pinion 23. A shaft 24 journaled in brackets 26 has gear 27 meshing with pinion 23 whereby continuous rotation is imparted to shaft 24. Shaft 24 carries a gear 28 which is engaged by a gear 29 secured to a shaft 31 journaled in brackets 32 and 33. Adjacent to the end journaled in bracket 33, shaft 31 has secured thereto a pinion 34 (Fig. 3) which is engaged by a gear 36 secured to a short shaft 37 that is journaled in bracket 38 carried by bracket 33. Shaft 37 supports and drives, through a spring loaded friction clutch, a gear 39 with which is meshed a gear 41 secured to shaft 42 which is rotatably supported by brackets 43. Shaft 42 is normally restrained from rotating in response to the torque continuously applied by the spring loaded friction clutch of shaft 37 by an escapement mechanism which will be described later.

Shaft 42 has fixed thereto in spaced relation a pair of sprockets 44 each of which has the periphery thereof provided with feed pins 46. In alignment with the two sprockets 44 are sprockets 47 secured to shaft 48 which is rota-

tionally supported by brackets 26 above shaft 24. Sprockets 47 are likewise provided with feed pins 50. Endless bands 49 extend from each of the sprockets 44 to the corresponding sprockets 47. Bands 49 may be fabricated from any durable thin sheet material, such as sheet steel, and each provided with feed perforations 51 spaced in accordance with the spacing of feed pins 46 and 50 of sprockets 44 and 47 so that when shaft 42 is permitted to rotate, bands 49 travel in endless paths. Bands 49 are provided with feed pins 52 similar to sprocket feed pins 46, and these pins are disposed intermediate each two feed perforations 51. Endless bands 49 serve to support and feed, through the transmitting mechanism, a page-width paper which carries the code signal combinations to be transmitted. One such page is indicated by the reference numeral 53 and it will be observed that this page is provided with perforations arranged along the margins thereof to be fitted over and engaged by pins 46, 48 and 52. A similar message page for controlling a transmitter is described in Patent 1,060,939 granted May 6, 1913, to Louis M. Potts. Retaining strips 54, having tunnels through which feed pins 46 and 52 may pass, are mounted above bands 49 in close proximity thereto to prevent page 53 from shifting out of position on band 49.

Shaft 31 supports and imparts continuous rotation to gear 56 and the driving element 57 of a jaw clutch. Driven element 58 of the jaw clutch is slidably axially of shaft 31 and is urged toward driving element 57 by compression spring 59. The jaw clutch of elements 57 and 58 is of the single revolution type, and disengagement is effected by clutch throwout lever 61 cooperating with flange 62 carried by driven element 58. Driven element 58 of the clutch mechanism is splined to sleeve 63 which is mounted on shaft 31 and is free of the shaft so as to be capable of remaining stationary while the shaft rotates and which constitutes the element that is driven intermittently by the clutch mechanism.

Sleeve 63 has secured thereto a cam 64 which is engaged by a spring biased detent 66. Detent 66 operates through cam 64 to apply a torque to sleeve 63 at the instant of disengagement of clutch elements 57 and 58 by clutch throwout lever 61 to effect complete separation of the clutch elements and prevent clutch teeth chattering in the stop position.

Sleeve 63 supports for rotation independently thereof a drum 67 (Fig. 3) having sprocket pins 68 uniformly spaced around the periphery thereof. A ratchet 69 is secured to drum 67. At a point remote from drums 67 and 81, opposed brackets 70 and 71 (Fig. 1) are adjustably mounted by screws extending through slots in the bases of the brackets and clamping the brackets to the base of the transmitter. Bracket 71 supports stud 72 in the same horizontal plane as clutch driven sleeve 63. Stud 72 supports freely rotatable drum 73 which is similar to drum 67 and is provided with similar sprocket feed pins 74. An endless flexible band 76 of any opaque material, such as thin metal, extends around and between drums 67 and 73 and is provided in one margin thereof with feed perforations 75 spaced to be entered by sprocket feed pins 68 and 74. The upper tangent run of endless band 76 extends across the transmitter just below the upper tangent run of message page feed bands 49 and is arranged to move, as will be set forth in detail later, in the direction

indicated by the arrow. Band 76 is provided in the body thereof with transversely extending slots 78 of sufficient width and length to register with all of the signal impulse elements of a single code-signal combination carried by message page 53. It will be apparent as band 76 is moved in the direction indicated by the arrow, a slot 78 will register successively with the several code-signal combinations representing a line of the message.

Band 76 is preferably equal in length to an integral multiple of the circumference of drums 67 and 73, which in turn is preferably equal to the length of the longest line of signal combinations which the message page 53 is expected to accommodate plus the width of one code-signal combination. The spacing of slots 78 along band 76 is equal to the circumference of drums 67 and 73. These relationships facilitate the resetting of band 76, in a manner which will be described later, to bring a slot 78 into position to scan a line beginning with the first signal combination.

Clutch driven sleeve 63 supports, in spaced relation to drum 67, a freely rotatable drum 81 provided with sprocket feed pins 82 in the periphery thereof. Drum 81 has secured thereto ratchet 83 which is also rotatable independently of sleeve 63 by which it is supported. A stud 85 carried by bracket 70 rotatably supports a drum 84 similar to drum 81 and spaced from drum 73 in accordance with the spacing between drums 67 and 81 carried by sleeve 63. Drum 84 is provided in the periphery thereof with sprocket feed pins 86, and drums 81 and 84 are just enough larger in diameter than drums 67 and 73 to enable an endless flexible band 87 of opaque material to overlie and overlap band 76. Band 87 is provided adjacent to one edge with spaced feed perforations 88 that are entered by sprocket feed pins 82 and 86. Band 87 is provided with a plurality of sets of longitudinally extending slots each set consisting of a number of slots 89 equal in number to the signal elements of a signal combination and preferably disposed in obliquely offset arrangement so that as band 87 travels in the direction indicated by the arrow, the slots 89 of a set register successively with transversely extending slots 78 of band 76. The distance from the beginning of one set of slots 89 to the beginning of the next set is equal to the circumference of drums 81 and 84, and band 87 is equal in length to an integral multiple of the circumference of drums 81 and 84 so that as the drums make one complete revolution any one of the sets of slots 89 will be brought exactly into the position occupied by the preceding set at the beginning of the revolution.

As set forth in the preceding paragraphs, each of the scanning bands 76 and 87 is equal in length to an integral multiple of the circumference of the sprockets by which it will be supported. If both bands are proportioned according to the same multiple, the outer band, which is supported on the larger sprockets, must have the axes of its sprockets farther apart than those of the sprockets supporting the inner band, if the outer band is to be drawn taut between its sprockets. The slots in brackets 70 and 71 permit both bands to be drawn taut and permit studs 72 and 85 to be disposed in different vertical planes.

The driving of drums 67 and 81 to effect signal scanning movement of bands 76 and 87 will now be described. A shaft 92 (Fig. 3), rotatably

supported in brackets 32 and 33 below shaft 31, has loosely mounted thereon gear 91 which meshes with continuously driven gear 56 carried by shaft 31. A positive drive jaw clutch mechanism similar to that previously described and comprising driving element 93, axially movable element 94, compression spring 96, and clutch throwout lever 97 (Fig. 2) is associated with shaft 92. Driving element 93 is secured to gear 91 so as to be continuously rotatable therewith, and driven element 94 is positively connected to shaft 92 so that, when clutch elements 93 and 94 are engaged, shaft 92 is rotated and, when clutch elements 93 and 94 are held apart by clutch throwout lever 97, shaft 92 is stationary although gear 91 continues to rotate. Cam 98 secured to shaft 92 and detent 99 cooperate in the manner set forth with reference to cam 64 and detent 66 to effect complete separation of clutch elements 93 and 94. The gear ratio of gears 56 and 91 is unity so that shaft 92, when driven, rotates at the same velocity as shaft 31.

A gear 101 fixed to shaft 92 meshes with a gear 102 carried loosely by sleeve 63 and freely rotatable thereupon. On the face which is presented toward ratchet 83, gear 102 carries a stud 103 upon which is pivotally mounted a pawl 104 urged into engagement with the teeth of ratchet 83 by a spring (not shown). The pawl 104 and ratchet 83 serve as a driving connection between gear 102 and drum 81, whereby band 87 is continuously moved in the direction indicated by the arrow when shaft 92 is rotated. As previously stated, the circumference of drum 81 equals the distance between the corresponding parts of any two adjacent sets of slots 89 in band 87. Thus it will be apparent that if the first slot 89 of a set is about to come into registry with a signal combination on message page 53 as drum 81 begins to rotate, the first slot of the next set will be about to come into registry with the same signal combination at the completion of one revolution of drum 81. The ratio between gears 101 and 102 is such that gear 101 in one revolution will impart to gear 102 slightly more than one revolution, the excess representing, in peripheral movement of drum 81, the distance from a vertical edge of one signal combination to the corresponding edge of the next signal combination in a line. Thus for a single revolution of shaft 92, one entire set of slots 89 will scan a signal combination, and the first slot of the next set will be presented in readiness to scan the next signal combination. The advancement of successive sets of slots 89 into position to scan successive signal combinations is automatically controlled and effected through the small difference between angular velocities of gears 101 and 102, the velocity of the latter of which is the higher. The slots 89 in band 87 should be so proportioned in relation to the velocity of travel of the band that a signal impulse of the desired length is generated while a slot traverses a fixed point, such as a signal element on the message page.

The slots in band 87 represent the elements of permutation code signal combinations, and the impulses initiated during scanning may be marking or spacing depending upon the nature of code impressions on the message page scanned by the slots. The space between sets of slots also represents impulses, preferably the rest and start impulses, by which proper phasing is maintained in a start-stop system. The portions of band 87 representing both of these signal impulses are blank, due to the provision of a sepa-

rate scanning system for generating the rest impulse, as will presently appear. The rest impulse might, however, be represented by a slot, since it is ordinarily of marking nature, in which case each signal combination carried by the message page would have a marking element to be scanned by the rest impulse slot. The auxiliary scanning system to be described later could then be dispensed with, but extra space would be occupied on each page by the rest impulse elements.

The transmitter herein disclosed may be arranged to generate impulses for five or six unit code but preferably generates six unit code combinations. The reason for this preference is that when a five unit code is employed, code combinations are assigned to shift and unshift functions to effect letters or figures printing. These shift and unshift combinations are not representative of characters to be printed, and their employment in a message page might result in the introduction of extra spaces in the printed message accompanying the signal combinations, and in order to transmit lines of standard length, excessively wide message pages with longer than average lines of signal combinations might be required.

The six unit code affords ample number of signal combinations for letters and figures selection without a shift. It thus permits the code combinations and associated message characters to be arranged exactly in accordance with the normal spacing of typewritten reading matter. The transmitter may operate directly a six unit permutation printer, or it may be employed to operate a five unit code printer if there be interposed between the transmitter and the printer a code translating system such as that disclosed in Patent 2,152,772, granted April 4, 1939, to L. M. Potts.

Shaft 92 has secured thereto a cam 104 (Figs. 2, 3, and 6), which is disposed in an elongated aperture 106 in a lever 107 pivoted on and suspended from sleeve 63 carried by shaft 31. Lever 107 carries a stud 108 which pivotally supports pawl 109. Pawl 109 is aligned with and is spring urged into engagement with ratchet 69 secured to drum 67. The oscillation of lever 107 by cam 104, as shaft 92 rotates, causes ratchet 69 to be advanced step by step to effect advancement of transverse slot 78 in band 76 from one to another of the signal combinations successively each time shaft 92 performs one revolution. A spring biased check pawl 111 (Fig. 6) is pivotally mounted upon a stationary portion of the transmitter mechanism and engages ratchet 69 to prevent backward rotation of ratchet 69 and to insure that pawl 109 picks up successive teeth thereof upon each operation by cam 104.

As shown in Fig. 6, a considerable amount of overtravel is provided in the return movement of pawl 109 to pick up the next tooth in ratchet 69, and this results in lost motion in the forward movement, whereby the pawl does not advance ratchet 69 until near the end of its forward movement. The reason for this is that band 76 must remain stationary until all of the character code slots of a set in band 87 have scanned a signal combination, and must then be stepped to its next position into registry with the next signal combination during the interval it is being traversed by a blank portion of band 87 between two sets of slots.

It will be apparent from the description thus far that with a message page supported on bands 49 with a line of signal combinations disposed in

the zone traversed by slots 78 and 89, a slot 78 will register successively with the signal combinations, and that while the slot 78 is in registry with each of the signal combinations, a set of 5 slots 89 will pass across slot 78 and thus scan successively the several signal elements of a signal combination. As shown in Figs. 1, 2, and 5, a source of illumination comprising an elongated lamp 116 of sufficient length to illuminate a full 10 line of signal combinations is stationarily mounted just above bands 49 and bands 76 and 87 so that message page 53 may pass between lamp 116 and bands 76 and 87 and may be illuminated thereby. A cover 117 is fitted over lamp 116 and 15 confines the illumination to message page 53. Below the upper runs of bands 76 and 87 there is mounted a housing 118 (Figs. 2 and 5) which contains a photo-electric cell 119 and a reflector 121 (Fig. 5). Reflector 121 is set at such an angle as to reflect light from lamp 116 on the 20 light sensitive electrode 122 of photo-electric cell 119, and the reflector and photo-cell are substantially coextensive with lamp 116 so as to be able to respond to light transmitted through any portion of a line of message page 53. The photo-electric cell could be employed without the reflector, but it would have to be placed between the upper and lower runs of bands 76 and 87. The mounting of the cell and its removal and reinsertion are simplified by having the cell offset with respect to the scanning bands.

The message page 53 may be opaque to light supplied by lamp 116, and the signal elements contained therein may be of a light transmitting 25 nature. They may comprise apertures made by perforating the page in accordance with the signal combinations to be transmitted, or they may comprise portions of the page rendered translucent by treatment with oil or other suitable material. With this arrangement the light transmitting portions of the signal combinations represent marking conditions and permit the photo-electric cell to be activated to initiate marking impulses. According to an alternative arrangement, the message page may be translucent and the signal combinations may be printed thereon so as to render the marking signal elements 30 opaque. The photo-electric cell will then be non-responsive to marking signal elements, and it may be so connected electrically to the telegraph line that marking signals are initiated in response to an inert condition of the photo-electric cell. As still another alternative, the signal combinations may be printed in an opposite arrangement; namely, printing the spacing elements with ink 35 so as to render them opaque, leaving unprinted areas of the translucent page to represent marking conditions. When marking areas are light transmitting, the initiation of impulses by the photo-electric cell is direct, an activated condition of the cell resulting in marking impulses, and an inert condition resulting in spacing impulses. When marking areas are opaque, a reversal of control condition between the cell and the telegraph line is necessary, so that a marking impulse may be initiated in response to an inert condition of the cell. The characters represented by the signal combinations may be 40 printed directly above the signal combination, so that the message page constitutes legible copy as well as a transmitter controlling form.

Each of the slots 89 in band 87 is arranged to register with one of the signal elements of a signal combination while slot 78 is in registry with an entire signal combination, and those of

slots 89 which register with a perforation or translucent area of page 53 permit light to pass through to photo-electric cell 119 to effect activation of the cell. The transmitting mechanism, as disclosed herein, is arranged to transmit start-stop permutation code signals which, as is well known, are equal length combinations of marking and spacing signals preceded by a start signal, which is of spacing nature, and followed by a stop or rest signal, which is of marking nature. Assuming that translucent areas represent marking signals and spacing signals are generated by permitting no light to reach photo-electric cell 119, the start signal may be considered as represented by a portion of the blank space in band 87 between any two sets of scanning slots 89. The stop or rest impulse involves the generation of a marking signal, and if no apertures in bands 76 and 87 and marking elements on the page are provided to permit light to reach photo-electric cell 119 to effect the generation of the rest impulse, a separate optical system, as heretofore mentioned, may be provided for the generation of the rest impulse.

This system, as shown in Fig. 3, comprises an auxiliary lamp 123, auxiliary photo-electric cell 124, and a disc 126 fixed to shaft 92 and provided with an aperture 127 through which light may be transmitted from lamp 123 to photo-cell 124. Since scanning bands 76 and 87 are driven by shaft 92 through gear 101 and cam 104, and since the scanning of one signal combination is accomplished by one revolution of shaft 92, perfect timing of the generation of the stop or rest impulse under the control of disc 126 can be maintained so that after the last slot 89 of a set has scanned the last signal element of a signal combination, aperture 127 in disc 126 can come into the path of light from lamp 123 to photo-electric cell 124 to effect generation of the stop impulse. The time required for the first slot 89 of a set to come into registry with the first signal element after transmission of the rest impulse has ceased represents the start impulse as does also that portion of the blank space in band 87 between two sets of slots 89, which traverses an arbitrarily selected point during the time interval mentioned.

There are certain functions to be performed in the transmitter which correspond to functions in the receiving printer which may be responding to the signals generated in the transmitter. For example, after a complete line of signal combinations has been scanned, it is necessary to advance bands 49 to bring a new line of signal combinations into position to be scanned, and it is also necessary to reset bands 76 and 87 corresponding to a carriage return operation, so that a slot 18 in band 76 shall be presented in position to scan the first signal combination of the new line, and one of the sets of slots 89 shall be prepared to scan that signal combination in timed relation to the presentation of slot 18. It is, therefore, necessary that there shall be, local to the transmitter, a mechanism for interpreting the signals generated in and transmitted from the transmitter, so that those signals which represent functions shall be made effective to control those functions in the transmitter itself.

As shown in Fig. 7, there is associated with shaft 92 a selector mechanism responsive to all of the signal combinations generated in the transmitter. This selector mechanism may be generally similar to that disclosed in Patent 1,745,633 granted February 4, 1930, to S. Morton et al. or

in Patent 1,937,376 granted November 28, 1933, to Walter J. Zenner and comprises a selector magnet 131 having an armature 132, an armature lever 133 for controlling the setting of selector lever 134, and a sword and T-selector mechanism which includes sword levers 137 and T-levers 138 and which is controlled jointly by selector lever 134 and by selector cam assembly 139 carried by shaft 92, to effect the setting of T-levers 138 in accordance with the signal combination impressed upon selector magnet 131. Selector cam assembly 139 is fixed to shaft 92 so as to be positively driven or arrested thereby, which is an arrangement different from that ordinarily employed in receiving selector mechanisms as exemplified in Patents 1,745,633 and 1,937,376, in that it is the usual custom to drive the selector cam assembly through a friction clutch mechanism, so that it may be arrested when signal combinations are not being received while permitting its driving shaft to rotate continuously in order that rotation may be imparted to the selector cam assembly as soon as the start impulse of the signal combination is received by the selector magnet. Selector cam assemblies in start-stop receiving printers are usually driven at a slightly faster rate than are transmitter shafts, in order that at the end of each cycle the cam assembly may be synchronized with the transmitter by arresting it briefly, which not only makes desirable the friction clutch connection, but also necessitates an angular sequence of receiving cams different from that of transmitting cams. In the present structure, the selector cam assembly rotates at the speed of transmitting shaft 92, and therefore the angular setting of cams thereon may be comparable with that of transmitting cams, rather than with those of printer receiving cam assemblies shown in Patents 1,745,633 and 1,937,376. It will be found by reference to a description of operation, which will appear later, that shaft 92 is not rotating when signal combinations are not being generated in the photo-electric cells and applied to selector magnet 131, and therefore that a friction drive and magnet controlled stop member for selector cam assembly 139 are not required. T-levers 138 are connected by intermediate levers 141 to end-wise slidably notched code bars 142, so that for each characteristic setting of T-levers 138 in accordance with a signal combination, a corresponding setting of code bars 142 is effected. Code bars 142 are provided with notches as at 143 arranged along an edge of each code bar in accordance with the signaling code upon which the mechanism is operated. For certain settings of the code bars, these being the settings representative of function selections, one or more alignments of notches extending transversely of the group of code bars 142 is effected.

One of the functions that a printing telegraph apparatus operating on signals transmitted from the herein disclosed photo-electric transmitter is required to perform periodically is the carriage return operation by which the carriage is restored to a beginning of line position for the printing of a new line. Corresponding to the carriage return function in a printer is a function required to be performed in the transmitting mechanism involving the resetting of scanning bands 76 and 87 in proper relation to scan a new line of signal combinations beginning with the first combination in the line. For the performance of this function, there is provided a function bar 144 (Figs. 2, 4, 5, and 7) which has a portion ex-

tending across the set of notched code bars 142 and in alignment with which a clearance of notches may be presented for the selection of bar 144. Bar 144 is translatable supported on pivot pin 146 (Fig. 5) movable in slot 147 and is biased for engagement with the edges of code bars 142 by tension spring 148. A universal operating bail 151, pivoted at 152 and spanning all of the positions in which alignments of notches in code bars 142 may be effected, has an arm 153 (Fig. 1) engaging a lever 154 operated by cam 156 carried by shaft 92.

Once in each revolution of shaft 92, cam 156 operates lever 154 to permit universal operating bail 151 to rotate counterclockwise from its normal position, as viewed in Fig. 5, under the influence of tension spring 157 and immediately restores it to extreme clockwise or normal position against the tension of the spring. Function bar 144 has in its upper edge a clearance 158, a slightly higher portion 159, and between these a notch 161. Clearance 158 permits bar 144 to rest against the edges of code bars 142. Higher portion 159 is in the path of universal operating bail 151 and together with other similar bars is engaged by the bail as it rocks counterclockwise to effect withdrawal of bar 144 and others from engagement with code bars 142, leaving the code bars free to move. As bail 151 returns to its normal position, it permits bar 144 to return into engagement with code bars 142, and if an alignment of notches is presented to function bar 144, the bar enters the alignment of notches, its free end thereby being lifted sufficiently to cause notch 161 to become hooked on the lower end of operating bail 151. Continued motion of bail 151 to its normal position results in leftward movement (as viewed in Fig. 5) of bar 144. Above function bar 144 there is mounted on bracket 163 a pivot rod 162 which supports a bail 164 that is substantially coextensive with the universal operating bail 151 and also supports a bell crank lever 166. Bell crank lever 166 comprises twin arms 167 and 168 in the operating path of which bail 164 is disposed, and a single arm 169. Arm 167 of bell crank 166 depends along the side of function bar 144, and the bar is provided with lug 171 for engaging arm 167 and rocking bell crank 166 clockwise as function bar 144 is moved to its extreme left-hand position. Arm 169 of bell crank 166 is connected by link 172 to clutch throwout lever 61 associated with the positive drive clutch carried by shaft 31. The downward movement of link 172, resulting from the rocking of bell crank lever 166, causes clutch throwout lever 61 to be withdrawn from restraining engagement with driven element 58 of the clutch, which is thus permitted to move into engagement with driving element 57 under the influence of compression spring 59. A connection for the driving of sleeve 63 is thus established. Bell crank lever 166, as it is rocked in clockwise direction, imparts clockwise rocking movement to bail 164. Bail 164 is provided with an arm 173, which is connected by link 174 with clutch throwout lever 97 associated with the positive drive clutch comprising elements 93 and 94 carried by shaft 92. The downward movement of link 174, as bail 164 is actuated, results in the rocking of clutch throwout lever into position to disengage driven element 94 from driving element 93 as the shaft 92 reaches its rest position in which position aperture 127 in disc 126 is presented in registry with the light path between lamp 123 and photo-electric cell 75

124 so that a stop or rest condition is impressed upon the telegraph line. Each time that bail 164 is operated, clutch throwout lever 97 is presented in clutch disengaging position and shaft 92 is arrested. A safety yielding interconnection between link 174 and clutch throwout lever 97 is afforded by pin 176, slot 177, and tension spring 178.

In the foregoing description of elements supported by clutch driven sleeve 63, none has been identified as being positively connected to the sleeve except cam 64. Referring now to Figs. 1, 2, and 6, reference numerals 181 and 182 indicate arms secured to sleeve 63 and extending radially therefrom between band feeding drums 67 and 81 and adjacent the inner faces thereof. Drums 67 and 81 have projections 183 and 184 on the inner faces thereof presented in the path of arms 181 and 182 of sleeve 63. Projections 183 and 184 are wedge-shaped, and arms 181 and 182 of sleeve 63 are preferably moderately flexible, so that drums 67 and 81 are capable of continuous rotation in the direction of travel of bands 76 and 87, by the flexing of arms 181 and 182 as the sloping faces of projections 183 and 184 engage them in passing. In actual practice, only drum 81 operates through a plurality of revolutions during the scanning of a line, drum 67 never completing a revolution before restoration of the drums to line beginning position. Therefore, only projection 184 needs to be wedge-shaped and only arm 182 needs to be flexible; however, it may be convenient to provide similar arrangements for both drums, for uniformity, and also because there may be occasion, such as in the making of adjustments, for rotating drum 67 through several revolutions while arm 181 remains stationary.

The rotation of sleeve 63, when clutch lever 61 is tripped by function bar 144, causes arms 181 and 182 to revolve. The motion is in the same direction as that imparted to drums 67 and 81 during signal scanning operations, and as the drums are then stationary, due to arrestment of shaft 92 by clutch lever 97, the scanning band restoring arms 181 and 182 revolve idly until they have traversed the distances previously traversed by drums 67 and 81 in scanning the characters in the line just completed, which in the case of drum 81 is the actual distance traveled, while in the case of drum 67 is an integrated distance accumulated in the successive rotations of the drum, whereupon arms 181 and 182 come into engagement with projections 183 and 184 and rotate the drums through the remaining distance which sleeve 63 rotates in completing one cycle.

Flange 62 of driven clutch element 58 has a cam apex 186 (Fig. 4) on the periphery thereof. A lever 187 pivoted at 188 extends substantially horizontally below shaft 31 and has upstanding cam follower 189 in engagement with the periphery of flange 62. At the distal end from the point of pivotal mounting 188, lever 187 is pivoted to a link 191 which is guided in slotted bracket 190 and has near its lower end a laterally extending projection 192 (Figs. 5 and 15) disposed above function bar 144. Near the end of the cycle of operation of driven clutch element 58, cam projection 186 on flange 62 rocks lever 187 downwardly to effect downward movement of link 191. Link 191 in turn rocks function bar 144 downwardly to effect disengagement of notch 161 thereof from universal operating bail 151. Function bar 144, bell crank lever 166,

and bail 164 are thus permitted to return to their normal position. The restoration of bell crank lever 166 to its normal position results in the restoration of clutch throwout lever 61 in position to arrest clutch element 58 at end of a complete revolution thereof. The restoration of bail 164 to normal position results in withdrawal of clutch throwout lever 97 from restraining engagement with driven clutch element 94 carried by shaft 92 whereby clutch elements 93 and 94 are permitted to become reengaged and shaft 92 begins to rotate.

In order that drums 67 and 81 shall not over-travel, after arms 182 and 183 have been brought to rest, they are provided with stop lugs 193, Fig. 15, extending from the outer or exposed faces for cooperation with two stop levers 194. Levers 194 are pivoted at 196 and are notched at their upper ends to provide shoulders 197 for presentation in the path of stop lugs 193. Since it is essential that shoulders 197 of levers 194 be presented in the path of stop lugs 193 until the end of the cycle of operation of driven clutch element 68, and since it is likewise essential that shoulders 197 be withdrawn from the paths of stop lugs 193 before shaft 92, operating through gear 101 and cam 104, can rotate drums 81 and 67 respectively any appreciable distance, it has been found convenient to connect drum stop levers 194 to clutch throwout lever 97 which controls the operation of shaft 92. Accordingly, an arm 198 is added to clutch throwout lever 97 and is connected at its outer end to the lower ends of drums stop levers 194 by link 199. From this it will be observed that when bail 164 is operated to present clutch throwout lever in position to disengage driven elements 94 from driving elements 93, levers 194 are rocked counterclockwise, as viewed in Fig. 4, to present shoulders 197 in the paths of stop lugs 193. Since 40 drum 81, which is the only one that operates through more than one revolution between resettings, is driven from shaft 92, there is no possibility of interference by lever 194 with the normal operation of drum 81, shaft 92 now being arrested. The restoration of levers 194 to unblocking position is effected when clutch throwout lever 97 is withdrawn to permit shaft 92 to resume operation. Thus, drums 67 and 81 are always arrested in the same position after a band resetting operation and since, as previously stated, the distance between scanning apertures 18 on band 76 is equal to the circumference of drum 67, and the distance from the beginning of one set of slots 89 carried by band 87 to the beginning of the next set is equal to the circumference of drum 81, bands 76 and 87 are always reset in position to scan the first character of a line in proper synchronism.

It was previously stated that bell crank lever 166 is provided with twin arms 167 and 168 and the relationship of function operating bar 144 to arm 167 has been set forth. A function bar 201 bears the same relation to arm 168 that function bar 144 bears to 167, so that upon selection of either of function bars 144 or 201 and operation thereof by universal operating bail 151, a scanning band resetting operation will be performed. The disengagement of function bar 201 from universal operating bail 151 is accomplished by the same means provided for disengaging bar 144; namely, link 191. Link 191 is provided at its lower end with a slot 202 in which function bar 201 is disposed. Slot 202 is of sufficient depth that when function bar 201 is unselected it will

not be rocked when function bar 144 is rocked to effect disengagement from bail 151. The circumstances under which the scanning band resetting function may require dual selection by function bars 144 or 201 will be described later.

After the scanning of a line of signal combinations has been completed, it is also necessary to advance the message page to present a new line of signal combinations to the scanning bands. This function corresponds to the line feed function in a printing telegraph receiver and may be responsive to the line feed code combination transmitted for controlling the printing telegraph receiver. For controlling this function, there is provided a line feed function bar 206 (Figs. 4 and 5) which is similar to function bar 144 and is provided on one face with a lug 207 (Fig. 4). A bell crank lever 208 similar to bell crank lever 166 is rockably mounted on shaft 162 and has twin arms 209 and 211, the former of which is presented in the path of lug 207. Bell crank lever 208 has an arm 212 which is connected by link 213 to an arm 214, Fig. 5, of a pawl 216 which, with pawl 217 and ratchet 218, constitute an escapement mechanism. Pawls 216 and 217 are pivoted at 219, and pawl 216 is provided with a laterally extending arm 221, which engages the inner edge of pawl 217 and imparts clockwise rotation thereto when pawl 216 is rotated clockwise. A tension spring 222 biases pawl 217 counterclockwise, and this pawl imparts a corresponding bias to pawl 216 through arm 221. Scape wheel 218 is secured to shaft 42, which is constantly under torque and which is effective to advance message-feed bands 49. The spacing of the teeth of escapement wheel 218 corresponds to the spacing of lines of code signal records on message page 53 so that when scape wheel 218 rotates a distance equaling the angle between corresponding edges of adjacent teeth, one line of signal records is moved out of registry with the scanning bands and the next line is presented in registry therewith.

When function bar 206 has been selected and moved to its extreme left-hand position by universal operating bail 151, as viewed in Fig. 5, line feed function bell crank lever 208 is rocked in clockwise direction, thus rocking bail 164 clockwise to effect arrestment of shaft 92, and moving link 213 upwardly. The upward movement of link 213 causes pawls 216 and 217 to operate as a true escapement, pawl 216 being rocked clockwise to present it in the path of the teeth of scape wheel 218, and pawl 217 being withdrawn. Scape wheel 218 is permitted to rotate until pawl 216 arrests it, which occurs before the wheel has rotated an angular distance corresponding to the distance between two teeth.

The disengagement of function bar 206 from universal operating bail 151 is effected by a cam 223 secured to message page band idler shaft 48. Cam 223 is provided with a plurality of lobes 224 corresponding in number and spacing to the teeth of escapement wheel 218. A bell crank lever 226 pivoted at 228 has at the free end of one of its arms a portion 227 projecting into the path of lobes 224, and has at the free end of its other arm pivotal connection 229 with a link 231 depending therefrom. Link 231 carries at its lower end a transversely extending pin 232, a portion of which extends under the end of function bar 206. Bell crank 226 is biased in counterclockwise direction by tension spring 233. When pawls 216 and 217 are actuated to permit page feed ratchet feed wheel to rotate until checked

by pawl 216, rotation is imparted by bands 49 to shaft 48 through sprockets 47, and cam 223 is rotated an angular distance equal to that of escapement wheel 218. The rotation of cam 223 is sufficient to cause one of the lobes 224 to encounter end 227 of bell crank 226 and rock this bell crank lever clockwise, thus lifting link 231. Pin 232 being thus lifted imparts clockwise rocking movement to line feed function bar 206 so that it becomes disengaged from universal operating bail 151 and returns to its extreme right-hand position, as viewed in Fig. 5. The restoration of function bar 206 to its normal position allows bell crank lever 208 and bail 164 to return to their normal positions also. The restoration of bail 164 to its normal position results in re-starting of shaft 92 as set forth in the description of the scanning band resetting operation. Restoration of bell crank lever 208 to its extreme counterclockwise position results in restoration of pawls 216 and 217 to like positions. Pawl 217 is thus presented in the path of the tooth immediately following the one which has just previously been permitted to escape, and pawl 216 is withdrawn from escapement wheel checking position so that the escapement wheel 218 is permitted to rotate the additional distance necessary to bring the next tooth into engagement with pawl 217 which holds the ratchet wheel from further rotation. As previously stated, bell crank lever 208 has twin arms 209 and 211 the former of which is engaged and operated by function bar 206. A function bar 234 similar to bar 206 may be provided for engagement with and operation of arm 211 of bell crank lever 208. Thus the line feed function may be performed in response to either of two signal combinations, and the circumstances under which such control may be desirable will be described later. Function bar 234 is provided with a slot 235 (Fig. 5) through which pin 232 carried by link 231 extends, so that when function bar 234 has been selected, engaged by operating bail 151, and operated, it may be released therefrom by link 231.

Another function, which has utility in the page transmitter herein described but which has no counterpart in many printing telegraph receivers, is message feed. By means of this function, after all of the lines of signal combinations carried by the page have been transmitted, the entire page 50 may be delivered from the transmitter, a feeding distance corresponding to a number of line feed operations in a single operation. For the selection of the message-feed function, there is provided a function bar 236 (Figs. 4 and 11) similar to function bar 206 and similarly provided with a lug 237 in the path of which is disposed arm 238 of a bell crank lever 239 pivoted upon rod 162. A portion of bail 164 is presented in the path of arm 238 of bell crank lever 239, so that when motion is imparted to the bell crank by function bar 233, clutch element 94, carried by shaft 92, will be disengaged from clutch element 93 and shaft 92 will be arrested to stop scanning. Arm 241 of bell crank lever 239 is connected by link 242 (Figs. 4 and 5) to one end of a lever 243 which is pivoted at 219 coaxially with the pivotal mounting of line feed escapement pawls 217 and 218. At the end opposite to that engaged by link 242, lever 243 is provided with a laterally extending arm 244 similar to arm 221 of escapement pawl 216 and similarly engaging the inner edge of escapement pawl 217. It will thus be observed that when link 242 is moved upwardly due to clockwise rocking of bell crank lever 239, 75

lever 243 will also be rocked clockwise and will withdraw pawl 217 from restraining engagement with escapement wheel 218. Pawl 216 is not at this time operated so that escapement wheel 218 is not checked but is permitted to rotate until pawl 217 is again presented in blocking relation thereto.

Tape feed sprocket idler shaft 48 has secured thereto, adjacent to line feed control cam follower 227, a message-feed control cam 246 which is provided with a single apex 247. A cam follower bell crank lever 248 similar to bell crank 226 is rockably mounted at 228 and is connected by a link 252 to the left-hand end of function bar 15 236 (concealed by function bars 206 and 234 in Fig. 5) so that, when apex 247 of cam 246 rocks bell crank lever 248 clockwise and moves link 252 upwardly, function bar 236 will be disengaged from universal operating bail 151, and bell crank lever 239 and bail 164 will return to their normal position. Pawl 217 is then permitted to respond to the influence of tension spring 222 to engage and arrest scape wheel 218.

Referring to Figs. 2 and 4, consideration will now be given to the circumstances under which the performance of a function under the control of either of two function bars may be desirable. For this consideration it should be borne in mind that bell crank lever 166, which controls carriage return for scanning band resetting, may be actuated by either of function bars 144 and 201, and bell crank lever 208, which controls line feed, may be operated by either of function bars 206 and 234. In some printing telegraph receiver mechanisms, the line feed and carriage return function mechanisms are made responsive to a single code combination so that upon the reception of that combination both functions are initiated simultaneously. In other printers, separate line feed and carriage return code combinations are assigned to control the two functions and both combinations must be received in order to effect the performance of both functions. In receiver mechanisms of the latter class, it is usually customary to transmit the carriage return signal before the line feed signal for the reason that a greater interval of time is usually required to accomplish carriage return operation than that required for line feed and the time for the completion of the carriage return operation is afforded during the performance of line feed.

The transmitter disclosed herein is particularly adapted to the control of those printing telegraph receivers in which the line feed and carriage return operations are initiated in response to a single signal combination. It will be apparent that if separate line feed and carriage return signals appear at the end of a line of message material, the first of the two signals will be transmitted and the function corresponding to that signal will be performed in the transmitter. Thus, if the carriage return signal is the first of the two function signals and is scanned, the bands will be reset to begin the scanning of a new line and the line feed signal appearing at the end of the line will not be transmitted nor will a line feed function be performed in the transmitter. Conversely, if the line feed signal precedes the carriage return signal, the message page will be advanced in response to the scanning of the line feed signal and the carriage return signal will then have been moved out of registry with the scanning bands. If a single code combination is employed in selecting both carriage return and line feed operations, code bars 142 will be notched

identically with respect to two function bars, such as 144 and 206, so that upon the setting of the code bars in positions corresponding to the combined line feed and carriage return signal function bars 144 and 206 will be selected and simultaneously operated by universal operating bail 151 to effect the rocking simultaneously of bell cranks 166 and 208 and the performance of both functions.

It may under certain circumstances be desirable to effect a line feed without also resetting the scanning bands or returning the carriage of the receiving printer. For example, headings may be disposed in staggered arrangement so that after the portion of the heading in one line has been scanned, the portion in the next line may be scanned from its beginning by bringing it into registry with the scanning belt by a line feed operation without restoring the scanning band to the beginning of line position. Also where the last line of a paragraph is very short it may be possible to proceed to the scanning of the next line, which would in all probability be indented, without resetting the scanning bands. Provision for this situation may be had by cutting code bars 142 so that function bar 234 shall be selected in response to a signal assigned to line feed only, and bell crank 208 alone will be rocked to effect advancement of the message page without resetting of the scanning band.

Since the message-feed function results in the ejection of the page from the transmitter, there is probably no circumstance under which it would be desirable to begin scanning the first line of the next message page at any other position than that designated herein as the beginning of the line position. The simultaneous resetting of the scanning bands for the scanning of a new message page would therefore probably be desired invariably. This could be accomplished by cutting the code bars identically with respect to message-feed function bar 236 and dual carriage return function bar 201 so that both function bars would be selected in response to the message-feed signal and would effect simultaneous rocking of bell crank lever 166 and 241.

In the foregoing description of line feed and carriage return operation, a system of function bar selection was described in which, in response to a single code combination, two function bars 144 and 206 are selected to initiate line feed and scanning band resetting simultaneously. This enables function bar 234 to be selectable for initiating a line feed operation alone but necessitates the use of a receiving printer in which the line feed and carriage return operations are jointly responsive to a single signal combination. By cutting code bars 142 differently the transmitter herein described may be arranged to operate a receiving printer in which the carriage return and line feed operations are performed independently each in response to its own assigned signal combination. For this arrangement a message page may carry at the end of each line of the message a carriage return signal followed by a line feed signal. In order that the scanning mechanism may be permitted to scan the line feed signal, it is necessary that it shall not respond to the scanning of the carriage return signal with the performance of a function. Accordingly, code bars 142 are so notched that none of the function bars shall be selected when the code bars have been set in position representing the carriage return signal, however, the carriage return signal will be trans-

mitted over the telegraph line and will initiate the carriage return operation in the receiving printer. Following the scanning of the carriage return signal, the line feed signal is scanned and code bars 142 are set in accordance with this signal. The notching of the code bars 142 must be such that a carriage return function bar shall respond to the line feed signal, and accordingly, function bar 144 is selected simultaneously with either of bars 206 and 234. The two functions are thus initiated simultaneously in the transmitter in response to the line feed signal and are performed while the line feed operation is being performed in the receiving printer. The transmitter function mechanism was, however, idle during the initiation of the carriage return operation in the receiving printer. Since no function is performed by the transmitter in response to the carriage return signal, and scanning band resetting is performed in response to the line feed signal, there can be no independent line feed function which will be effective in the transmitter to accomplish line feed only, unless there be provided in the code two line feed signals, one of which might be designated as ordinary and to which the line feed mechanism and band resetting mechanism of the transmitter would be simultaneously responsive, and the other of which might be designated as extraordinary to which the line feed mechanism only of the transmitter would be responsive.

In order that the transmitter may be operated continuously without requiring the manual insertion of page after page of messages as the transmission of signals from each page is completed and the message page is ejected from the transmitter, a message storage magazine is provided. The construction of the message magazine is shown in Figs. 8 and 9. Referring to Fig. 9, reference numeral 261 designates a platform which is mounted to slope downwardly toward message-feed bands 49 and which terminates just above message-feed idler sprockets 47. Platform 261 is provided with an integral frame-edge 262 which serves to maintain the message pages in proper alignment upon platform 261 and the right-hand end of which, as viewed in Fig. 9, is separated and spaced rightwardly from the lowermost end of platform 261 producing a message-exit slot. A pivot rod 263 is supported by the sides 262 and this rod extends across platform 261 in parallel relation thereto. A bail 264 is pivotally supported by rod 263 just inside frame 262, and the transverse portion of the bail is disposed in the space between the right-hand end of platform 261 and the right-hand end of frame-edge 262. Just below one of the side arms of bail 264, platform 261 is provided with a slot through which extends a cam follower arm 266 integral with one side arm of the bail. A cam 267 is secured to message-feed idler shaft 48 and the periphery of the cam is engaged by cam follower arm 266. Cam 267 is provided with a depression so that once in each cycle of rotation of shaft 48, bail 264 is permitted to rock clockwise in response to biasing tension spring 268 and is thereafter restored to its counterclockwise position. The purpose of bail 264 is to depress into engagement with message-feed bands 49 the foremost end of a message page supported by platform 261.

At equidistant points throughout their length, message-feed bands 49 are provided with feed pins 269 which differ from pins 52 in that they are claw-shaped. A similar construction is dis-

closed in Patent No. 1,060,939. Pins 269 are carried by leaf springs 271 secured to the inner side of bands 49 and are disposed through apertures in the bands. Leaf springs 271 are so tensioned that their free ends tend to draw away from band 49, whereby pins 269 are normally withdrawn from the outer surface of bands 49. When that portion of a band 49 which carries a spring 271 passes over one of the sprockets 47, spring 271 is flexed into engagement with the underside of the band and pin 269, carried by it, is projected through the aperture in the belt. The arrangement of pins 269 along band 49 is such that when the depression in cam 267 is presented to cam follower 266 so that ball 264 is permitted to rock clockwise, a claw-shaped pin 269 on each of bands 49 is presented directly beneath the first of the marginal perforations in a message page which has its foremost end presented adjacent to the right-hand end, Fig. 9, of frame 262 so that the foremost perforations are fitted over claw-shaped pins 269 by ball 264 as it rocks clockwise. From this it will be apparent that the spacing between any two claw-shaped pins 269 is equal to the circumference of sprockets 47, and further that the length of a band 49 is equal to an integral multiple of that circumference, so that pins 269 are uniformly spaced upon band 49. The timing of the mechanism is such that ball 264 is restored to its normal position before claw 269 has been carried forward to a point at which it would strike the transverse portion of the ball, and the right-hand end of frame 262 may be provided with clearances in alignment with the pins carried by bands 49 through which claw-shaped pins 269 may pass. Claw-shaped pins 269 carry the message page forward and as soon as they move free of any supporting surfaces, such as sprockets 47, they are retracted by their springs 271. By the time they are permitted to be retracted, other feed pins carried by bands 49 have entered the marginal perforations in the message page so that engagement of the page by the claw-shaped pins is no longer required. In order that pins 269 shall not be projected through their apertures in bands 49 by message-feed sprockets 44, each of the latter may have a recess 270 in the periphery thereof which will accommodate spring 271 and pins 269 so that the claw-shaped pins shall not interfere with the ejection of a message page from the transmitter. Also, since the upper run of bands 49 is very close to the scanning bands, it is desirable to maintain pins 269 projected through their apertures in bands 49 as these pins pass across the scanning bands, as pins in their retracted positions would interfere with the operation of the scanning bands. Accordingly, pin supporting strips 265 of sufficient length to accomplish the purpose outlined above may be supported between bands 49 and the scanning bands as shown in Figs. 1 and 5.

At a point remote from its lowermost edge, platform 261 carries rotatable shaft 272 which may be mounted in journal brackets (not shown) depending from the underside of platform 261. Shaft 272 has secured thereto a pair of sprocket feed wheels 273 spaced apart in accordance with the spacing between message-feed bands 49 so that their feed pins 274 may register with the marginal perforations in a message page deposited in the message magazine and confined between the sides of its frame 262. Platform 261 is provided with apertures in alignment with sprocket feed wheels 273 and of sufficient size to

permit feed pins 274 to project successively above the surface of platform 261. Shaft 272 also has secured thereto a ratchet wheel 276 which is engaged by a jockey detent 277 arranged to arrest ratchet wheel 276 in predetermined angular positions. The angular disposition of ratchet wheel 276 with respect to sprocket wheel 273 is such that in each position of arrestment of shaft 272, a pin 274 on each of sprocket wheels 273 projects through platform 261 approximately normal thereto. Shaft 272 pivotally supports a plate 278 which carries pivotally mounted ratchet feed pawl 279. Pawl 279 is biased into engagement with ratchet 276 by tension spring 281. A link 282 connects plate 278 to one end of a lever 283 pivotally mounted at 284 on a bracket 286 which depends from the underside of platform 261 adjacent to the lowermost end thereof. The other end of lever 283 is disposed in the path of a pin 289 extending from the face of a disc 288 fixed to message-feed idler shaft 48. When pin 289 engages lever 283 during the rotation of disc 288, it imparts counterclockwise rocking movement to lever 283, which in turn moves link 282 leftwardly, as viewed in Fig. 9. Link 282 in turn rocks plate 278 clockwise, which, through pawl 279 and ratchet wheel 276, rotates a sprocket wheel 273 clockwise one ratchet feed step. After pin 289 passes the end of lever 283, the latter and link 282 and plate 278 are restored to normal position by tension spring 291 which engages link 282. The distance from the right-hand end of frame 262, as viewed in Fig. 9, to the point at which a pin 274 of sprocket wheel 273 projects through platform 261 is such that when a standard length message page has its foremost end abutting the right-hand end of frame 262, its most remote feed perforations are disposed upon pins 274 of ratchet feed wheel 273. The timing of the rotation of shaft 272 by disc 288 is such that at about the time ball 264 rocks clockwise to engage a message page with claw-shaped pins 269 whereby the message begins to be moved forward by bands 49, ratchet 276 is operated to free the page from engagement with sprocket feed wheels 273, and the peripheral speed of sprockets 273 should be compatible with the peripheral speed of sprockets 47, so that mutilation of the message-feed perforations shall not occur. A plurality of message pages may be stored in the message magazine in overlap arrangement, each page being set back from the one below it a distance equal to that between feed perforation as shown in Fig. 8. A pair of pressure rolls 292 rotatably mounted upon pins carried by the left-hand ends (Fig. 9) of the arms 293 pivotally mounted on rod 263 and connected together by brace 290 serves to retain a pile-up of message pages in engagement with sprocket wheels 273. Each time ratchet 276 is operated, all of the message pages are shifted downwardly along the inclined platform 261, the lowermost message, if in position to be engaged by pins 269, is advanced free of sprocket 273 so that it may be advanced by band 49 to the transmitting position, and the message next above it is brought into position where its foremost end is in position to be next picked up by bands 49.

The spindle which supports one of the pressure rolls 292 also supports a roll 294 which has a relatively deep annular groove 295 intermediate its ends. Below platform 261 a roll 296 thin enough to enter groove 295 of roll 294 is rotatably supported in alignment with said groove by one end 70 of a lever 297 pivoted to bracket 288. A tension

spring 299 biases lever 297 in clockwise direction, and platform 261 is provided with an aperture at the point of registry of roll 296 with roll 292 so that when there are no message pages stored on platform 261, lever 297 may rock clockwise and roll 296 may enter groove 295 in roll 294. However, when platform 261 is supporting one or more message pages, rolls 294 and 296 are held separated by the message pages. At its other end, lever 297 engages one of a pair of contact springs 301 and holds the springs engaged when rolls 294 and 296 are maintained separated by a message page. When the supply of message pages is exhausted and lever 297 rocks clockwise, contact springs 301 separate and open an electrical circuit to be described later, which remains open until more message pages are placed in the magazine.

A roll 302 similar to roll 294 and provided with annular groove 303 is rotatably mounted in the free end of an arm 304 that is pivotally mounted on rod 263. A tension spring 306 biases arm 304 in clockwise direction, and arm 304 extends rightwardly well beyond the end of frame 262 so that roll 302 may engage and be supported by a message page adjacent to the scanning position. A thin roll 306 capable of entering groove 303 in roll 302 is rotatably supported by one end of a lever 307, which is pivotally supported by bracket 308. A tension spring 309 biases lever 307 counterclockwise so that roll 306 seeks entrance into groove 303 of roll 302. The presence of a message page between rolls 302 and 306 prevents counterclockwise rocking movement of lever 307. At its other end, lever 307 engages one of a pair of contact springs 311 and maintains those springs in engagement when lever 307 is retained in its extreme clockwise position. A pin 312 is carried by the underside of lever 307 directly above shaft 48, and the pin engages the periphery of a cam 313 fixed to shaft 48. Cam 313 is provided with a single depression in the periphery thereof, so that at a predetermined instant in a cycle of operation of shaft 48, cam 313 permits lever 307 to rotate counterclockwise if there is at that time no message page interposed between rolls 302 and 306. Thus, it will be observed that lever 307 is not operable to permit opening of contact spring 311 the instant that a message page is withdrawn from between rolls 302 and 306 but that such opening must await the presentation of the depression in the periphery of cam 313 to pin 312. The timing of the rocking of lever 307 with respect to the operation of other elements associated with shaft 48 or controlled thereby and the function of contact springs 311 in the electrical circuit will be described herein-after.

The electrical control system for the photoelectric transmitter is indicated diagrammatically in Fig. 12. Power cord 316, which may be plugged into any convenient source of power, is connected to power terminals 317 and 318. A circuit for a switching relay 319 is traced from power terminal 317 through conductor 321, conductor 322, contact springs 311, conductor 323, winding of switching relay 319, resistance 324, conductor 326 to power terminal 318. Thus, when contact springs 311 are engaged, switching relay 319 is energized and its contact tongue 327, which is connected by conductor 328 to conductor 321, is held in engagement with front contact 329 from which a conductive path may be traced through conductor 331, normally closed switch 332, winding of electromagnet 334, resistance 336, conduc-

tor 337, and conductor 326 to power terminal 318.

Electromagnet 334 has a mechanical function for an understanding of which reference may be had to Figs. 2 and 5. Armature 338 of magnet 334 is connected by link 339 to the free end of an arm 341 pivotally mounted upon shaft 162 which supports bail 164 and the function bell crank levers. Arm 341 is positioned between function bell cranks 166 and 208, and bail 164, which spans these bell cranks, is in the operating path of arm 341 so that when electromagnet 334 becomes deenergized and its armature 338 is retracted, bail 164 is rocked clockwise to effect arrestment of shaft 92 in the same manner that it is so-rocked upon operation of any of the selectable function bars. When magnet 334 again becomes energized, its armature 338 is attracted and through link 339, arm 341 is restored to its extreme counterclockwise position so that bail 164 is permitted to return to its counterclockwise position and the clutch, comprising elements 93 and 94, is tripped off. From this it will be observed that the operation of the scanning bands is supervised by message page follower lever 307 and cam 313 so that the scanning bands cannot perform idle scanning operations when no message page is positioned to be scanned. Switch 332 affords a manually operable control for stopping the transmitter for any desired purpose.

Referring again to Fig. 12, it will be observed that a conductive path may be traced from back contact 342 of relay 319 through conductor 343, contact springs 301, normally closed switch 344, conductor 346, winding of electromagnet 347, resistance 348, conductor 349, conductor 337, and conductor 326 to power terminal 318. It will be evident from this that when relay 319 is deenergized so that its contact tongue 327 engages back contact 343 and contact springs 301 are closed, electromagnet 347 will be energized. Stating the same condition from the standpoint of the operation of the transmitter, electromagnet 347 will be energized when there is one or more message pages in the message magazine awaiting transmission although there is no message page in the transmitter, the presence of message pages in the magazine being indicated by the closed condition of contact springs 301.

Electromagnet 347 also performs a mechanical function, an understanding of which may be had by reference to Figs. 2 and 5. The free end of armature 351 of electromagnet 347 is confined between the main body of previously identified link 252 and a hook-shaped finger 352 carried thereby. At its lower end link 252 is articulated to message-feed function bar 236, and upon energization of electromagnet 347, function bar 236 is shifted to effect operation of link 242 and withdrawal of pawl 217 from blocking engagement with scape wheel 218 in the same manner as if it had been operated by universal operating bail 151 upon selection by code bars 142. Switch 344 is provided for preventing the operation of magnet 347 as for convenience in testing and adjusting the magnet or related apparatus, or when inserting or rearranging messages in the storage magazine, so that a message-feed operation shall not be initiated at an improper time.

Since magnet 347 remains energized only as long as switching magnet 319 is deenergized, and the latter magnet can remain deenergized only as long as the recess in cam 313 is presented to the cam follower of lever 307, the rotation of scape wheel 218, upon withdrawal of message-

feed pawl 217, results in rotation of cam 313 and immediate closure of contacts 311. Magnet 319 is thus again energized and magnet 347 becomes deenergized. It is necessary to prolong the operation of message-feed bands 49 after magnet 347 becomes deenergized, in order to effect the advancement of messages in the magazine, or the presentation of the first line of signal combinations on a page, received from the magazine, in the scanning position. This can be accomplished by providing a latch to hold message-feed function bar 236 in operated position. Bar 236 will not at this time become latched on operating bail 151, because it is not rocked counterclockwise to present its notch in the path of bail 151, there being no selection of function bar 236 by code bars 142. Therefore, an additional latch must be provided.

As shown in Fig. 11, the frame of electromagnet 347 has pivoted thereto a latch lever 353 having a shoulder 354 positioned to drop behind a projection 356 of armature 351 when the armature is in attracted position. Latch lever 353 is biased in operative direction by a spring 357 and extends across link 252 above a pin 358 projecting laterally from one face of link 252. With this arrangement, armature 351, when attracted, will become latched upon shoulder 354 of lever 353, thus holding function bar 236 in operated position. When thereafter cam projection 247 rocks bell crank 248 clockwise and effects upward movement of link 252, pin 358 rocks latch lever 353 counterclockwise, whereby shoulder 354 is lifted out of engagement with armature projection 356, and function bar 236 is permitted to return to its normal position.

When function bar 236 is operated and held by bail 151, it may shift armature 351 through the rocking of link 252 to such an extent that the armature becomes latched on shoulder 354. This will not interfere with the normal operation and release of the function bar. The lifting of link 252 by cam projection 247 will result in the simultaneous tripping of latch lever 353 and the tripping of function bar 236 from engagement with bail 151.

Concurrently with the release of armature 351, the recess in cam 313 is presented to its follower, and if no message page has been presented between rolls 302 and 306, switching magnet 319 will become deenergized, magnet 347 will become energized and its armature 351 will be attracted and latched. Another message-feed operation seeking to present a page to the scanning position will thus be initiated.

Once in each revolution of disc 288 (Figs. 8 and 9) attending the successive message-feed function operations initiated by magnet 347, the magazine message-feed mechanism comprising lever 283, link 282, pawl 279, and ratchet 273 will be operated. Magazine message-feed ratchet 273 will thus be operated periodically and any message pages engaged thereby will be advanced step by step until the lowermost is presented in position to be engaged by claw-shaped pin 269 upon the next operation of bail 264. The message page will then be advanced by bands 49 between cooperating rolls 302 and 306, and contact springs 311 will be prevented from separating when cam 313 releases lever 307.

When neither the transmitter nor the message storage magazine contains a message page, contact springs 301 and 311 both become separated. The energizing circuit for magnet 334 is thus broken at front contact 329 and shaft 92 is ar-

rested through operation of link 339, lever arm 341, bail 164, link 174, and clutch throwout lever 97. The energizing circuit for magnet 347 is broken at contact spring 301 so that message-feed function bar 236 remains in its normal position and message-feed bands 49, scanning bands 76 and 87, and shaft 92 are arrested and remain in their normal or idle position.

At various points in the foregoing description, reference has been made to relative dimensions of message-feed bands and sprockets, the dimensions of the message page storage magazine, and the arrangement of feed pins. These characteristics have direct bearing upon the length of page that can be handled conveniently, and upon the timing of the page handling mechanism.

As previously stated, the spacing of the claw-shaped pins 269 on a band 49 is preferably equal to the circumference of the message feeding sprockets of the transmitter. The reason for this is that once in each revolution of the idler sprockets 41, mechanism actuated by cams carried by the idler sprocket shaft operates to deliver a message page from the magazine. When this occurs, the claw-shaped pins must be presented in position to accept and advance the message. It follows from this that each message page should not be longer than the distance between claw-shaped pins 269, for if they are, two successive claw-shaped pins on a band 49 will engage a single message page, which is of no advantage, and a message freshly delivered from the magazine may be deposited over a portion of the preceding message page, which is not desirable. Preferably, each page will be substantially equal in length to the spacing between successive claw-shaped pins. There will then be neither overlap nor gap between successive message pages.

The size of page that is to be used determines the dimensions of the page storage magazine. The distance from the end of frame 262 to the point at which pins 274 of sprocket 273 project through platform 261 shall be neither substantially greater nor less than the distance from the top of a page to the axis of the last feed perforation therein. If the pages should be too short, the sprockets 273 will not advance it into position to be engaged by claw-shaped pins 269. If it should be too long, it will not be moved clear of sprockets 273 when the claw-shaped pins attempt to deliver it to the scanning position in a single operation, and the feed perforations may be torn out. It will be evident that with the page storage magazine proportioned as outlined above, the right-hand end of frame 262 may serve as a guide for the positioning of the first of a supply of message pages. With the leading edge of the page abutting the end of frame 262, the last feed perforations on the page will be substantially in registry with sprocket pins 274.

In the event that special length message pages either longer or shorter than those the storage magazine is arranged to handle are to be used occasionally, they may be placed in the magazine singly, resting above the pressure rolls 292, as for example upon cross brace 290, and extending under rod 263 with the leading edge in position to be applied to the claw-shaped pins. Thus, the page will not be engaged by sprocket pins 274. A page of special length may be thus positioned for transmission ahead of messages in the magazine without removing those messages. It is, however, desirable to disable the message-feed mechanism of the magazine in order that mes-

sages engaged by the magazine sprocket shall not be advanced during the forwarding of the special size or rush message of any size by bands 49. This may be accomplished by the magazine message-feed pawl disabling mechanism shown in Fig. 13. A pawl shifting cam 366 having operating handle 368 is loosely supported on shaft 272 for rocking movement thereon adjacent to ratchet 276. Ratchet feed pawl 279 is provided with a pin 367 which engages the periphery of cam 366. At the point in its periphery normally presented to pin 367, cam 366 has a radius which permits the pawl to engage ratchet 276. In a clockwise direction from this point, the radius increases until it exceeds the maximum radius of ratchet 276, so that when cam 366 is rotated counterclockwise by means of handle 368, pawl 279 is cammed away from ratchet 276 until it is held entirely clear. The periphery of cam 366 is provided with two notches which a jockey 369 is adapted to enter when the cam is presented in either of its two positions. The jockey is pivoted coaxially with pawl 279 on plate 278, and when the plate is rocked by link 282, jockey 369 imparts a corresponding rocking movement to cam 366, so that the cam remains in whatever relation to pawl 279 it has been manually presented.

The disablement of pawl 279 by cam 366 permits shaft 272 to be rotated manually in either direction. Therefore, a knob 371 (Fig. 8) is secured to one end of shaft 272 for manual rotation of the shaft. For example, if messages are contained in the magazine with the lowermost presented in position to be transferred to the transmitter, and it is desired to transmit a rush message of the page size which the magazine accepts, cam 366 may be rocked counterclockwise to disable pawl 279, shaft 272 may be rotated counterclockwise one step to retract the messages in the magazine, and the rush message may be placed under pressure rolls 292, on top of the messages in the magazine, and in position to be next transferred to the transmitter, whereupon pawl 279 is restored to operative condition by 45 reverse operation of cam 366. In operating to advance the rush message in the transfer operation, the magazine mechanism will advance the messages in the magazine to the position they occupied before being retracted. Should there be 50 several rush message pages, the pages in the magazine may be retracted a number of ratchet steps equaling the number of rush pages, and the rush pages put in the magazine on top, in echelon arrangement, with the lowermost and foremost in position to be transferred. The pawl is then restored to operative condition and the regular messages will follow the rush messages into the transmitter automatically. When a message carried by a long page is to be transmitted, it is desirable not to restore the feed pawl to operative condition after the ratchet has been back-stepped, because the feeding of the long page into the transmitter would not be completed before the next message transfer operation occurs. The pawl should, therefore, remain retracted, and if switch 344 is opened, the transmitter will come to rest after the long page has been ejected therefrom.

As previously stated, the message-feed function mechanism of the transmitter, whether initiated by selection of function bar 236 or by operation of electromagnet 347, is arrested by cam 246 at the time that a pair of claw-shaped pins 269 have been advanced to a position to present

the first line of a message page in scanning location. It follows from this that lever 307 controlling contact springs 311 should be released to test for the presence or absence of a page in the transmitter at the time that the feed mechanism is arrested under the above outlined condition. This operating condition is indicated in Fig. 9 wherein the recess in cam 313 is shown presented to follower 312, which is prevented from entering the recess to permit separation of contact springs 311 because rolls 302 and 306 are held apart by a message page. As indicated, the message page has not been drawn entirely out of the magazine, the distance from the message pick-up position to the scanning position being less than a page length. Therefore, claw-shaped pins 269 for receiving the next message page have not yet reached receiving position, and magazine message-feed pin 289 and the recess in cam 267 are correspondingly remote from lever 283 and follower arm 266 respectively.

In Fig. 10 the message pick-up mechanism is shown with the claw-shaped pins 269 advanced to message receiving position. The message which had been extending into the magazine has been drawn entirely out, and its trailing edge is seen to be just clear of the leading edge of the lowermost page in the magazine. Cam follower 266 has entered the recess in cam 267 and bail 264 has depressed the leading portion of the lowermost page in the magazine into the path of pins 269. Pin 289 is about to operate the magazine message-feed mechanism, and the recess in cam 313 is remote from follower pin 312.

Referring again to Fig. 12, the signal transmitting circuit is shown in the upper portion thereof. Lamps 116 and 123 for activating photo-electric cells 119 and 124, respectively, are connected to power terminal 317 by conductors 361 and 321, and to power terminal 318 by conductors 362 and 326. Photo-electric cells 119 and 124 are connected in parallel across the input of a power supply and signal amplifier indicated schematically at 363. One terminal of the output of amplifier 363 is connected through the winding of selector magnet 131 of the transmitter to telegraph line 364 to which, at a remote point, selector magnet 365 of a printing telegraph receiver mechanism may be connected in the usual way. Thus, signaling impulses generated in the photo-electric cells are amplified and impressed upon the telegraph line through selector magnet 131 in the transmitter, which interprets the transmitted signals locally and initiates functions.

Summarizing the general operation of the transmitter, details of operation of which have been set forth at various points in the description of the mechanisms, the message-storage magazine receives and stores messages for delivery successively to the page supporting and advancing bands of the transmitter. The delivery of these message pages is under the control of the bands, so that synchronized operation results. When the foremost message page in the magazine is transferred to the page handling bands, all of the pages in the magazine are advanced one step. After the transfer, the message advances step by step toward the scanning position as the transmission of the message preceding it continues. When the message-feed signal at end of the message page being scanned becomes effective, that page is delivered out of the scanning position, and the page following it is advanced into position for scanning of the first

line, and is there arrested. Immediately the scanning bands are set in operation and the first line of signal combinations is scanned combination by combination in succession by continuous motion of the scanning band having sets of longitudinal slots and step-by-step movement of the band having transverse slots.

As each signal combination is scanned, the impingement of a beam of light upon the photo-electric cell is correspondingly controlled and signal impulses are thus generated, including phasing impulses. These impulses are impressed upon a telegraph line, and are also applied to a selector mechanism local to the transmitter. The selector mechanism controls the setting of selector bars, which are set for every code combination transmitted, but which effect only a few actual selections responsive to a few function signals. Line feed, carriage return, and message feed are characteristic functions. In response to a carriage return signal the scanning bands are moved by special means, in the same direction in which they travel for scanning, into position preparatory to scanning the first character of a line and are there arrested momentarily, after which scanning of the line begins. When the line-feed function is selected, the page handling bands are advanced one step to present the next line of signal combinations in position to be scanned by the reset bands.

The final signal in any message page is preferably a message-feed signal, in response to which the message page is advanced out of scanning position by advancement of the message-feed bands, and the next message is brought into position for scanning of the first line and is there arrested. There is also a magnet control of the message-feed mechanism whereby messages contained in the storage magazine remotely from the transfer position will be advanced step by step, when there is no message in the transmitter, until a message page is delivered to transmitting position. When there are no message pages stored in the magazine, and a message is being transmitted, the scanning, transmitting, and all message feeding mechanisms will come to rest upon the advancement of the page out of scanning position in response to a message-feed signal at the end of the message.

From the foregoing description, it will be observed that the photo-electric transmitter in accordance with the invention will transmit signal combinations capable of controlling commercially available printing telegraph receiver mechanisms under the control of page width forms having the signal combinations arranged thereon in lines and will automatically insert necessary synchronizing impulses. The transmitter mechanism will interpret the signal combination it is impressing upon the telegraph line and will respond to those signals which represent functional operations by performing functions necessarily incident to the scanning of successive lines of signal combination. The transmitter will automatically eject a message page after the transmission of the signal combinations contained therein has been completed and will automatically receive page after page of message material from a message page storage magazine as rapidly as the transmission of message material from a page is completed, regardless of the length of message material contained upon a page and without delay, so that substantially continuous transmission of signals may be accomplished without continuous supervision.

Although a particular embodiment of the invention has been shown in the drawings and described in the accompanying specification, it will be understood that the invention is not limited to the particular arrangement of parts and details of construction herein disclosed, but that the invention is capable of modification, rearrangement, and substitution of parts and alteration in any other respect within the scope of the appended claims.

What is claimed is:

1. In a telegraph transmitter adapted to be controlled by record material carrying signaling indicia arranged in successive parallel lines as in ordinary reading matter, means for photo-electrically scanning each signal combination in a line in succession and each line in succession, means for generating signaling impulses according to the signal combinations scanned, and means for generating synchronizing impulses between sets of impulses corresponding to signal combinations.
2. In a telegraph transmitter adapted to be controlled by record material carrying signaling indicia arranged in successive parallel lines, photo-electric means for generating signaling impulses, means for illuminating all of the elementary areas of a signal combination simultaneously, and means for rendering the illumination of each elementary area of a signal combination selectively effective in succession upon said photo-electric means.
3. In a telegraph transmitter adapted to be controlled by record material carrying signaling indicia arranged in successive lines, a stationarily mounted photo-sensitive device, a stationarily mounted exciter lamp for supplying illumination to said signaling indicia and thence to said photo-sensitive device, means for scanning the signaling indicia and for thereby controlling the excitation of said photo-sensitive device jointly with said signaling indicia, and means for stationarily supporting said record material during the scanning of a line of signaling indicia, said scanning means constituting the sole means for determining the sequence of scanning.
4. In a telegraph transmitter adapted to be controlled by record material carrying character signaling indicia arranged in successive lines, means for scanning the signaling indicia for each character in a line successively, and means for generating signaling impulses including a photo-sensitive device having a different portion of the sensitive surface effective in the generation of impulses for each successive character signal in a line.
5. In a telegraph transmitter adapted to be controlled by record material carrying signal combinations arranged in successive lines, means for illuminating said signal combinations, photo-sensitive means for generating impulses in accordance with said signal combinations, and a plurality of scanning elements, one of which determines the sequence of scanning the elements of a signal combination, and another of which determines the succession of scanning of the signal combinations.
6. In a telegraph transmitter adapted to be controlled by record material carrying signal combinations arranged in successive lines, a light beam, scanning means for periodically interrupting the light beam, means for effecting relative motion between said scanning means and the elements of a code combination and between said scanning means and successive code combina-

tions, and means controlled by said scanning means for transmitting a succession of impulses representing a line of message matter upon a single traversal of said line of signal combinations by said scanning means.

7. In a start-stop telegraph transmitter, a message scanning shutter device, a photo-sensitive element variably controlled by said shutter device for generating code signal impulses, another photo-sensitive device, and another shutter device effecting invariable control over said other photo-sensitive device for generating start-stop impulses to accompany groups of said code signal impulses.

8. In a telegraph transmitter adapted to be controlled by record material having code impressions, means for sensing the code impressions successively, means for moving the sensing means past the record material during sensing, means for generating code signals in accordance with the code impressions, and means responsive to generated code signals for controlling the movement of said sensing means past said record material.

9. In a telegraph transmitter adapted to be controlled by record material having signaling indicia arranged thereon in successive lines, means for illuminating all of the indicia in a line simultaneously, photo-sensitive impulse generating means, and means for rendering the illumination of said line of indicia effective upon said photo-sensitive means by successive elements of each signal combination and by successive signal combinations of said line.

10. In a telegraph transmitter adapted to be controlled by record material having signal combinations impressed thereon, means for illuminating said record material, photo-sensitive means for generating impulses, scanning means for controlling the generation of impulses comprising endless bands, means for moving one of said bands continuously, and means for moving the other of said bands intermittently.

11. In a photo-electric telegraph transmitter, a source of illumination, photo-sensitive impulse generating means, signal scanning means interposed between said source and said photo-sensitive means, said scanning means including overlapping endless bands, one of said bands having an aperture adapted to register with all the elements of a signal combination simultaneously, and the other of said bands having a plurality of apertures adapted to register successively with the aperture of the first mentioned band, means for imparting intermittent movement to said one band, and means for imparting continuous movement to said other band.

12. In a photo-electric scanning mechanism, a pair of overlapping endless bands, sprockets for supporting said bands, a ratchet associated with one of the sprockets supporting each band, a pawl engaging each ratchet, one of said pawls carried by a rotatable member, another of said pawls carried by an oscillatable member, and means for driving said members.

13. In a photo-electric scanning mechanism, a pair of overlapping endless bands, sprockets for supporting said bands, means for moving said bands in the same direction at different speeds, and means operable selectively for moving said bands in the same direction at the same speeds.

14. In a photo-electric scanning mechanism, a pair of overlapping endless bands, one of said bands having a scanning aperture therein and the other having a set of scanning apertures,

sprockets for supporting said bands, means for moving said bands in the same direction at different speeds, and means operable selectively for moving said bands in the same direction at the same speeds to bring said apertures into predetermined positions.

15. In a photo-electric scanning mechanism a pair of overlapping endless bands, one of said bands having a plurality of transversely extending scanning apertures, and the other having a plurality of sets of longitudinally extending apertures, sprockets for supporting said bands, means for moving the band having transversely extending apertures intermittently to bring a single aperture thereof into successive scanning positions, and means for moving the other band in the same direction continuously at a speed such that successive sets of longitudinally extending apertures traverse the transversely extending aperture as it advances to successive scanning positions.

16. In a telegraph transmitter adapted to be controlled by record material carrying character indicia and function controlling indicia arranged in successive parallel lines, means for scanning the character and function controlling indicia, means for generating signal impulses in accordance with the character and function indicia, means local to the transmitter for selecting and initiating a plurality of functions simultaneously in response to a single function indicia, means actuated by the function initiating means for performing the functions, means also controlled by the function initiating means for interrupting the scanning of indicia, and means controlled by the function performing means for restarting the scanning of indicia upon completion of the function requiring the greater cyclic time.

17. In combination with a telegraph transmitter adapted to be controlled by record material comprising individual pages, and including means for supporting and advancing the pages individually, a message page storage magazine including means for engaging a plurality of pages at points in each differing from the points of engagement with the others, means for advancing said pages together, and means for transferring said pages to the page supporting means of said transmitter.

18. In combination with a telegraph transmitter adapted to be controlled by record material comprising individual pages, and including means for supporting and advancing the pages individually, a message page storage magazine including means for engaging a plurality of superposed pages at points longitudinally of each differing from the points of engagement with the others, means for actuating said page engaging means to effect advancement of said pages together, and means for transferring the most advanced of said pages to the page supporting and advancing means of said transmitter, said actuating means being operated in timed relation to the transfer of said page to the page supporting and advancing means of said transmitter.

19. In a telegraph transmitting mechanism adapted to be controlled by record material, means for supporting and advancing said record material, means for scanning said record material, means for generating telegraph signals in accordance with said scanning, means for controlling the operation of said supporting and advancing means in individual steps or continuously through a distance representing a plurality of steps, means for supplying individual pieces of record material to said supporting and ad-

vancing means, and means operable under the condition that a piece of record material is contained in said supplying means and none is approaching said scanning means for effecting repeated cycles of movement of said supporting and advancing means through distances representing a plurality of steps until a piece of record material from said supplying means is advanced by said supporting and advancing means.

20. In a telegraph transmitting mechanism adapted to be controlled by record material, means for scanning said record material, means for generating telegraph signals in accordance with said scanning, means for advancing the record material past said scanning mechanism, means controlled by said advancing means for supplying pieces of record material individually thereto, means associated with said supplying means and operable under the condition of exhaustion of the supply of pieces of record material for conditioning said advancing means for arrestment, and means controlled by said advancing means and operable upon arrestment under predetermined conditions for disabling said scanning mechanism.

21. In a telegraph transmitter adapted to be controlled by record material in page form having telegraph signal code combinations arranged side by side in lines transversely of the page, means for scanning said record material including a light shutter, means for producing relative movement between said light shutter and said record material within the space allotted to a code combination to effect the scanning of the code combination, and means for conditioning said light shutter for the scanning of the next code combination in a line.

22. In a telegraph transmitter adapted to be controlled by record material in page form having telegraph signal code combinations arranged side by side in lines transversely of the page, means for scanning said record material including a light shutter, means for moving the light shutter relative to the record material to effect scanning of successive code combinations in a line, and means for moving the light shutter relative to the page to bring it into position for scanning the next line of code combinations.

23. In a telegraph transmitter adapted to be controlled by record material having code impressions, means for sensing the code impressions successively, means for producing relative motion between the record material and the sensing means during sensing, means for generating signals in accordance with the code impressions, and selector means including notched permutation code bars responsive to the generated signals for controlling the relative motion between the record material and the signal sensing means.

24. In a telegraph transmitter adapted to be controlled by record material carrying signaling indicia arranged in successive lines, means for scanning said signaling indicia including a pair of overlapping endless bands for traversing said lines of signaling indicia, means for imparting to one of said bands a single cycle of operation for the scanning of a line, and means for imparting to the other of said bands a plurality of cycles of operation for the scanning of a line.

25. In a telegraph transmitter adapted to be controlled by record material carrying signaling indicia arranged in successive parallel lines, a magazine adapted to receive a plurality of sheets of record material in superposed contact-

ing relationship, and means under control of the indicia to control the operation of the magazine to deliver the sheets one after another.

26. In a telegraph transmitter adapted to be controlled by record material carrying signaling indicia arranged in successive parallel lines, a magazine adapted to receive a plurality of sheets of record material of a predetermined length only, means controlled by said transmitter for feeding the sheets one after another from said magazine into transmitting position, means for permitting the insertion of sheets of other lengths, and means for disabling the magazine when using sheets of other lengths.

27. In a telegraph transmitter adapted to be controlled by record material carrying signaling indicia arranged in successive lines, a magazine adapted to receive a plurality of sheets of record material, means for advancing sheets of record material through said transmitter individually, and means for advancing the sheets of record material in the magazine a line spacing distance while a record material sheet in the transmitter is advanced a sheet length distance.

28. In a photo-electric scanning mechanism, a pair of overlapping endless bands, sprockets for supporting said bands, a normally stationary rotatable shaft for supporting certain of said sprockets, a ratchet associated with each sprocket on the shaft, a pawl engaging each ratchet, one of said pawls carried by a rotatable member, another of said pawls carried by an oscillatable member, means for driving said members, and means carried by said shaft and engageable with the sprockets carried by the shaft for imparting rotation to the sprockets.

29. In a photo-electric scanning mechanism, a pair of overlapping endless scanning bands, sprockets for supporting said bands, a normally stationary rotatable shaft for supporting certain of said sprockets, a ratchet associated with each sprocket on the shaft, a pawl engaging each ratchet, one of said pawls carried by a rotatable member, another of said pawls carried by an oscillatable member, means for driving said members, means carried by said shaft for imparting rotation to said sprockets carried by the shaft, and yieldable means associated with the sprockets to be engaged by said rotation imparting means when said shaft is rotated and to yieldably pass said means when said sprockets are actuated by said pawls.

30. In a telegraph transmitter adapted to be controlled by record material carrying signaling indicia arranged in successive parallel lines and having marginal apertures, a pair of spaced endless bands for supporting said record material marginally, a pair of drivable sprockets and a pair of idler sprockets for supporting said bands, pins carried by said bands to enter the apertures in said record material for aligning said record material with respect to said bands and for establishing driving connection therebetween, means for driving said drivable sprockets, means for generating signals corresponding to said signaling indicia, and means responsive to generated signals for controlling the driving of said drivable sprockets.

31. In a telegraph transmitter adapted to be controlled by record material carrying signaling indicia and having marginal perforations, a pair of spaced endless bands for supporting said record material marginally, pins carried by said bands to enter the marginal perforations in said record material, a pair of drivable sprockets and

a pair of idler sprockets for supporting said bands, means for driving said drivable sprockets, means for generating signals corresponding to said signaling indicia, means responsive to generated signals for releasing said drivable sprockets to be driven, and means dependent upon the particular signal which effected the release of said drivable sprockets for controlling the arrestment of said sprockets.

32. In a photo-electric scanning mechanism, a pair of overlapping endless bands, one of said bands having a transverse aperture and the other having a plurality of longitudinally extending apertures, a pair of sprockets for supporting each of said bands, means for rotating one of the sprockets supporting the band having the transverse aperture step by step to bring said aperture into successive scanning positions, a pair of sprockets for supporting the other band, and means operable during the interval between the end of one stepping operation and the end of the next stepping operation for steadily rotating one of the sprockets supporting the band having the longitudinal apertures through a peripheral distance equal to that between the first aperture of one set and the first aperture of the next set plus the distance through which the periphery of the step by step rotatable sprocket is rotated in one stepping operation thereof.

33. Apparatus according to claim 32 in which the steadily rotatable sprocket rotates in the same direction as the step by step rotatable sprocket.

34. In a telegraph transmitter adapted to be controlled by record material in page form carrying signaling indicia arranged in lines extending transversely thereof as in ordinary reading matter, a source of illumination for said signaling indicia at least coextensive with the longest line of signaling indicia said record material is adapted to contain, a photo-electric device having a photo-sensitive electrode, at least coextensive with the longest line of signaling indicia said record material is adapted to contain, and means for scanning said signaling indicia to permit illumination to reach said electrode at successive points along the surface thereof as a line of indicia is scanned.

35. In a photo-electric scanning mechanism, a pair of overlapping endless bands, one of said bands having a plurality of uniformly spaced transverse apertures and the other having a plurality of uniformly spaced sets of apertures,

sprockets for supporting the transversely apertured band equal in circumference to the spacing of said transverse apertures, sprockets for supporting the longitudinally apertured band equal in circumference to the distance from any point along one set of apertures to the corresponding point along the next set of apertures,

means for rotating the sprockets supporting the transversely apertured band cyclically in uniform steps, and means for rotating the sprockets supporting said longitudinally apertured band in the same direction as the first mentioned sprockets continuously to the extent of one revolution plus the angle of cyclic stepping of the first mentioned sprockets for each cyclic stepping thereof.

36. In a telegraph transmitter adapted to be controlled by record material in page form having signaling indicia arranged thereon in successive lines, means for supporting a record page, means for generating telegraph signal impulses corresponding to the indicia carried by the record page, means responsive to generated signals for advancing the record page in steps, and means responsive solely to generated signals for advancing the record page through the distance of a plurality of steps by continuous motion.

37. In a telegraph transmitter adapted to be controlled by record material in page form having signaling indicia arranged thereon in successive lines, means for supporting a record page, means for generating telegraph signal impulses corresponding to the indicia carried by the page, means responsive to generated signals for advancing the page line by line, and means responsive solely to generated signals for advancing a record page clear of the impulse generating means.

38. In a telegraph transmitter adapted to be controlled by record material in page form having signaling indicia arranged thereon in successive lines, means for supporting a record page, means for generating telegraph signal impulses corresponding to indicia carried by the record page, means controlled by generated signals for advancing the record page line by line, and means responsive to generated signals for advancing a record page through the distance of a plurality of line by line steps by continuous motion irrespective of the ratio of the number of lines of indicia to the length of the record page.

LOUIS M. POTTS.
